UNITED STATES PATENT OFFICE.

WILBUR F. BURNS, OF BRIDGEPORT, CONNECTICUT, ASSIGNOR TO THE BURNS & BASSICK COMPANY, OF BRIDGEPORT, CONNECTICUT, A CORPORATION OF CONNECTICUT.

DESIGN FOR A GLASS KNOB.

47,068.

Specification for Design.

Patented Mar. 9, 1915.

Application filed January 2, 1915. Serial No. 275. Term of patent 3½ years.

To all whom it may concern:

Be it known that I, WILBUR F. BURNS, a citizen of the United States, residing at the city of Bridgeport, county of Fairfield, State of Connecticut, have invented a new, original, and ornamental Design for a Glass Knob, of which the following is a specification, reference being had to the accompanying drawing, forming part thereof.

Figure 1 is a front elevation of a knob

showing my new design, and Fig. 2 a side elevation thereof.

I claim:

The ornamental design for a glass knob, as shown.

WILBUR F. BURNS.
